UNITED STATES PATENT OFFICE.

GEORGE H. ROSE, OF BEN. AVON, PENNSYLVANIA.

INCLINED FURNACE HOIST.

Application filed January 16, 1923. Serial No. 618,002.

To all whom it may concern:

Be it known that I, GEORGE H. ROSE, a citizen of the United States, and resident of Ben Avon, in the county of Allegheny and State of Pennsylvania, have invented certain new and useful Improvements in Inclined Furnace Hoists, of which the following is a specification.

My invention relates to the inclined skip hoists or bridges of mechanically filled blast furnaces, and has for one object the provision of an inclined hoist that is entirely supported independent of the furnace stack and, in a manner, not affected in any way by expansion and contraction of the furnace shell.

Such hoists, when independently supported, will also have the advantages of permitting repairs to be made to the furnace shell and lining without interfering with the hoist or bridge and will eliminate strains heretofore caused by the weight of the bridge and pull of the cables on the bridge being transmitted to the furnace shell.

Another object of the invention is to provide an inclined skip hoist or bridge having an integral crane runway adapted to support a trolley for use in handling any of the several parts of the furnace tops when rebuilding or repairing the furnace top rigging.

Heretofore it has been the usual practice to support the upper end of the skip hoist or bridge on the top of the blast furnace by securing the supporting structure to the shell of the furnace. This practice caused the bridges to be constantly affected by expansion and contraction, which occurs in operation of the furnaces, with more or less damaging results. As pointed out above, the present invention eliminates these disadvantages.

In the drawings—

Figure 1 is a side elevation of a blast furnace having a skip hoist bridge constructed in accordance with this invention.

Figure 2 is a plan of the horizontal top portion of the bridge.

Figure 3 is a sectional elevation on the line III—III of Figure 1.

Figure 4 is an elevation of the rear leg or support for the bridge.

Figure 5 is a side elevation of a blast furnace having a slightly modified construction of skip hoist bridge.

Referring more particularly to the drawings, the numeral 2 designates the blast furnaces as a whole, which may be of any well known design. The furnace has the usual charging hopper 3 at its upper end adapted to receive the material from the skip hoists and deliver it to the charging bell. In the furnace illustrated, the charging bell is shown in dotted lines and comprises a duplex construction, consisting of an upper bell 4 and lower bell 5. The furnace 2 will not be further described in detail since it is not a part of this invention, except as combined with the novel skip hoist to be described.

A cast house 6 surrounds the lower portion of the furnace and serves to house the different mechanisms connected with the operation of the furnace.

The cast house 6 is of steel construction and has heavy rolled metal trusses 7 and a metal roof 8. The sides of the cast house generally are more or less open for the purpose of ventilation.

The skip hoist is of the well known inclined type and comprises an inclined track supporting portion 9 having its lower end mounted on a suitable abutment 10 and its upper end extending upwardly over the furnace 2 and supported on a suitable support 11, which extends upwardly from the side frame of the cast house. A cantilever portion 12 of the bridge extends beyond the furnace on a line at right angles to the vertical axis of the bridge and serves as a crane runway for a suitable crane trolley 13.

A second upright support 14 extends upwardly from the base of the furnace 2 and is secured to the portion 9 of the bridge intermediate its ends. It will thus be seen that the bridge is supported entirely independent of the blast furnace.

The track supporting portion 9 of the bridge is composed of girders 15 secured in spaced relation and braced by lateral bracing members 16. Suitable transverse track supporting beams 17 are secured between the side girders and support track rails 18, which form two tracks for the skip cars 19 which are operated in the usual manner by

cables 20. A suitable decking or flooring 17' is also secured on the laterals 16 and beams 17 to prevent spillage from the cars 19 falling through the bridge. A suitable 5 hoisting or operating mechanism for cables 20 is mounted in the hoist house 21 adjacent the bottom of the bridge.

A horizontal bridge platform 22 is secured to the upper end of the portion 9 of the 10 bridge and extends outward over the same. The outer end of the bridge platform 22 is supported by legs 23 extending upwardly from the side girders 15. The bridge platform 22 is adapted to support suitable 15 sheaves 24 for the cables 20.

The modified construction of Figure 5 is substantially the same as the preferred construction and therefore like parts will be designated by the same reference numerals 20 as used in the description given before and the description of such parts will be understood to apply to both constructions.

The principal differences in construction between the modified and preferred constructions are that in the modified construction the cast house 6 is not shown and may be omitted from around the furnace, and the rear support 11^a, which corresponds to the support 11 in the preferred construction, extends upwardly from the ground instead of from the top of the side wall of the cast house. The second support 14 for the track supporting portion 9 is omitted from the modified construction, the whole weight of 35 the bridge being supported by the abutment 10 and support 11^a.

The crane trolley and various details are omitted from this view so as to simplify it. However, it will be understood that such 40 details would be embodied in a completed bridge.

I claim:—

1. The combination with a blast furnace, of an inclined permanent skip hoist or bridge 45 extending upwardly along and over the top

of said furnace, said bridge having a cantilever upper end extending beyond the furnace on a line at right angles to the vertical axis of the furnace forming a crane runway, and suitable upright supports on opposite sides of said furnace, one of said supports being secured to said bridge at a point intermediate its ends and the other of said supports being secured to the bridge adjacent its upper end, said supports extending upwardly from bases free of said furnace. 55

2. The combination with a blast furnace having a cast house, of an inclined skip hoist or bridge extending upwardly along and over the top of said furnace, and suitable 60 upright supports on opposite sides of said furnace, one of said supports extending upwardly from the base of said cast house and secured intermediate the ends of said bridge, and the other of said supports extending upwardly from the top of one of the side walls of said cast house and being secured to said bridge adjacent its upper end, thereby supporting said bridge free of said furnace. 65

3. The combination with a blast furnace 70 having a cast house built around its base, of an inclined skip hoist or bridge extending upwardly along and over the top of said furnace, said bridge having a cantilever upper end extending beyond the furnace on a line at right angles to the vertical axis of the furnace forming a crane runway, and suitable upright supports on opposite sides of said furnace, one of said supports extending upwardly from the base of said cast 75 house and secured intermediate the ends of said bridge, and the other of said supports extending upwardly from the top of one of the side walls of said cast house and being secured to said bridge adjacent its upper end, thereby providing a supporting structure for 80 said bridge entirely free of said furnace. 85

In testimony whereof, I have hereunto signed my name.

GEORGE H. ROSE.
